UNITED STATES PATENT OFFICE.

BURT S. HARRISON, OF CHICAGO, ILLINOIS, ASSIGNOR TO DRYING SYSTEMS, INC., OF CHICAGO, ILLINOIS, A CORPORATION OF ILLINOIS.

ATOMIZER.

Application filed May 15, 1922. Serial No. 561,238.

To all whom it may concern:

Be it known that I, BURT S. HARRISON, a citizen of the United States of America, and a resident of Chicago, county of Cook, 5 and State of Illinois, have invented a new and useful Improvement in Atomizers, of which the following is a specification.

This invention relates to means for atomizing liquid or semi-liquids, useful for 10 numerous purposes such as in spray dryers but is herein described particularly as an oil burner.

With most types of oil burners only enough air is handled through the burner 15 to atomize the oil. The balance of air necessary for good combustion is siphoned in as secondary air by the injector action of the flame in the atomizer. The result is that the volume of air handled is variable depending upon the stack draft, the initial 20 air pressure, the size of the secondary air opening, and other conditions which interfere with the fixed and certain operation of the burner. It is also the case in most 25 burners that the mixture of the secondary air and the partially atomized fuel in the firing chamber is imperfect, resulting in imperfect combustion, for unless the thorough mixing and diffusion of the oil mist 30 with the air is accomplished before combustion, the partial burning of the oil particles surrounds them with the products of combustion and prevents their complete combustion.

35 It is the object of the present invention to make more certain and efficient the operation of an atomizer of this general class and to overcome the objections to the unreliable action of prior types of burners. 40 It is also an object of the invention to produce a practically noiseless oil burner.

The objects of the invention are accomplished by the device shown in the accompanying drawings, wherein,

45 Figure 1 is a longitudinal sectional view of an oil burner and air blower constructed in accordance with this invention.

Figure 2 is a plan view illustrating the general arrangement of the burner, blower, 50 motors, oil pump, relief valve, and piping.

Figure 3 is an enlarged longitudinal sectional view of the burner nozzle.

55 Figure 4 is an enlarged longitudinal sectional detail showing one of the bearings for the rotatable burner shaft.

Figure 5 is an end view of the stationary disk of the burner indicated on the line 5-5 of Figure 3.

In its general features, the invention as illustrated comprises a pair of coaxial disks 60 spaced apart slightly and one of which disks is dished on its inner surface so that the two together form an annular radially extending nozzle. One of these disks is rapidly rotated while the oil is delivered to 65 the nozzle along the shaft supporting the rotating disk. The outlet edge of one of the disks is sharpened around the inner edge of its periphery. By the pressure on the oil, through the rotation of one of the 70 disks, the oil is thrown outwardly in a more or less tangential direction by centrifugal force. A rapidly moving surrounding envelope of air travels transversely to the throw of the liquid. The latter 75 is not only finely atomized but thoroughly mixed with the air diffused through it and is delivered in a helical stream in the form of a diverging cone, this being found very effective for the intended purpose. Since 80 the liquid is delivered from between a revolving and a stationary disk, there is a grinding or rubbing action tending to thoroughly atomize the oil and keep the burner clean, the outlet never becoming clogged 85 or carbonized. The complete surrounding of the burner with an air current prevents any dripping of oil and by placing the atomizer in the center of the blower outlet all the air for combustion passes through the 90 burner and its quantity and speed are capable of regulation. The roaring noise of most burners, being due to the high pressure required of the air and oil in order to siphon in the secondary air, is hereby avoided since 95 all of the air is delivered under pressure in large volume at comparatively low velocity.

The regulation of the quantity of oil delivered is affected by varying the space between the two disks of the nozzle and the resulting increase in the pressure of the oil between the burner and the pump affects the operation of a relief valve in the oil pump line, permitting more of the oil pumped 105 to bypass back into the pump suction line. The air blower speed is controlled by its variable speed driving motor and the air is delivered through an adjustable nozzle surrounding the oil nozzle. Thus the 110

volume of air delivered depends upon the static pressure on the air and the free area opening of the nozzle.

Referring to the drawings, 1 indicates a rapidly rotating shaft preferably having a direct connection to a motor 2 at its rear end. At its forward end this shaft carries a disk 3 between which and a stationary disk 4 is an annular nozzle shaped outlet 5 for the oil. The oil is conducted to the nozzle from the oil pump 6 through the conduit 7, pressure relief valve 8, conduit 9, and longitudinal grooves 10 in the shaft 1. The oil pump is shown driven by a gear connection 11 with shaft 1. The oil relief valve serves to maintain any desired pressure on the oil by diverting, at a predetermined pressure, some of the oil through the bypass 12 to the pump feed pipe 13.

The adjustment of the nozzle space between the disks 3 and 4 is effected by means of a hexagonal nut 14 rigid with a bushing 15 threaded into a bearing 16 for the shaft 1. This bushing carries a sleeve or tube 17 surrounding shaft 1 and slidably in the bearing 18, the dished disk 4 is fast to the end of sleeve 17.

The blower 19 is of the peripheral discharge type having at its bottom a discharge opening 20 concentric with and surrounding sleeve 17 and shaft 1. A nozzle sleeve 21 is bolted to the blower outlet and is threaded at its end 22 to receive the adjustable nozzle 23 surrounding the oil directing disks 3 and 4. The fan 24 of the blower is rigid on the shaft 25 of the variable speed motor 26.

In the operation of the device, the blower is driven at a speed corresponding with the maximum volume and pressure required of the air to carry the atomized liquid as thrown from the revolving disk 3 on the shaft 1. The volume of air delivered depends upon the static pressure of the air and the adjustment of the air outlet nozzle 23 with respect to the oil outlet nozzle which it surrounds. When the nozzle 23 is screwed back upon the nozzle sleeve so that its forward end is in line with the revolving shaft disk 3, the free area will be a minimum while when the nozzle is screwed forward on the nozzle sleeve so that the revolving shaft disk is back of the diverging nozzle, the free opening will be a maximum. By varying the speed of the blower and at the same time the speed of the nozzle, any proportion of the air volume between the maximum and the minimum may be obtained.

Although but one specific embodiment of this invention has been herein shown and described, it will be understood that numerous details of the construction shown may be altered or omitted without departing from the spirit of this invention as defined by the following claims.

I claim:

1. A device of the class described comprising a pair of coaxial spaced disks, means for rotating one of said disks, means for delivering a liquid to the space between said disks, means for regulating the flow of such liquid by a provision for adjusting one of said disks toward and away from the other, a means for delivering air under pressure past the periphery of said disks, said means including a nozzle converging toward said disks whereby the air and atomized liquid are directed to a focal point outward of and in line with the axis of the disks. 80

2. A device of the class described comprising a pair of coaxial spaced disks, means for rotating one of said disks, means for delivering a liquid to the space between said disks, means for regulating the flow of such liquid by a provision for adjusting one of said disks toward and away from the other, a tapered nozzle enclosing said disks and adjustable longitudinally for varying the space between the peripheries of said disks and the walls of the nozzle, and means for delivering air under pressure to said nozzle. 90

3. An atomizer of the class described comprising a pair of closely spaced disks, means for rotating one of said disks, means for delivering a liquid to the space between said disks whereby it will be atomized by a relative motion between the disks and thrown outwardly by centrifugal action, means for causing air to travel past said disks in an axial direction, and an adjustable nozzle surrounding said disks for controlling the flow of air. 95

4. A device of the class described comprising a pair of coaxial minutely spaced apart disks, means for producing a relative rotation between said disks, means for delivering a liquid under pressure to the space between said disks, a nozzle spaced 110 from and surrounding said disks and adjustable axially with respect to the disks, and means for delivering air under pressure to said nozzle. 110

Signed at Chicago this 12th day of May 115
1922.

BURT S. HARRISON.
